(57) **CLAIM**

The ornamental design for a power transmission coil for contactless charging, as shown and described.

DESCRIPTION

FIG. 1 is a perspective view of a power transmission coil for contactless charging.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof; and,

FIG. 8 is another perspective view thereof, without the magnetic cover.
